LOUVER

Joseph Veneziano, 1982 Staunton Road,
Cleveland Heights, Ohio 44118

Filed May 13, 1970, Ser. No. 22,951

Term of patent 14 years

Int. Cl. D23—99

FIG. 1 is a front perspective view of a louver embodying my design;

FIG. 2 is a rear perspective view thereof;

FIG. 3 is a front elevational view; and

FIG. 4 is a side elevational view thereof.

The wall siding is shown in broken lines in FIGS. 1 through 4 for illustrative purposes only.

I claim:

The ornamental design for a louver, as shown and described.
